UNITED STATES PATENT OFFICE.

DANIEL FORBES, OF BROOKLYN, NEW YORK, ASSIGNOR TO GEORGE H. HIBBLER, OF SAME PLACE.

DESIGN FOR THE ORNAMENTATION OF BOWLS OR DISHES.

SPECIFICATION forming part of Design No. 19,642, dated February 11, 1890.

Application filed November 9, 1889. Serial No. 329,818. Term of patent 7 years.

To all whom it may concern:

Be it known that I, DANIEL FORBES, of Brooklyn, in Kings county, and State of New York, have originated and produced a Design 5 for Bowls, Dishes, &c., of which the following is a specification.

My design relates particularly to bowls and dishes of glassware.

In the accompanying illustrations, Figure 10 1 is a perspective side view of a bowl embodying the said design. Fig. 2 is a perspective view of the bottom of the bowl.

Similar letters of reference designate corresponding parts in both figures.

15 The salient features of the design consist of scalloped edges *a* and curved lines *b*, substantially coinciding with the ends of the scallops and diverging from the junction of the scallops toward the bottom of the bowl.

20 The curved lines *b*, belonging to each scallop *a*, intersect at several points—as, for example, at the points *c*. To clearly indicate what I mean by the lines *b* substantially coinciding with the ends of the scallops, I have made 25 dotted lines *b'* between certain of the lines *b* and corresponding scallop *a*. It will be seen that the edges of the scallops *a* are shown as being serrated or notched. The intersection of the lines *b* produces figures *d*, which are 30 substantially diamond-shaped. To indicate clearly the outlines of these figures, I have drawn lines from the four corners to the letter *d*. Lines *e*, extending substantially up and down, intersect the lines *b* and form fig-

ures *f*, which have substantially parallel sides 35 and pointed ends. The upper and lower series of figures *f*, I have shown as crossed by intersecting lines, which form diamond-shaped figures, and the lower series of said figures extend between two adjacent points of the 40 star. The intersection of the lines *e* with the lines *b* also form triangular figures *g*. At the center of the bottom of the bowl I have shown a large star-shaped figure *h*, and within this 45 a small star-shaped figure *i*.

What I claim as my design, and desire to secure by Letters Patent, is—

The design for the ornamentation of a bowl or dish herein shown and described, consisting of a large star-shaped figure at the bottom, a scalloped upper edge, curved lines diverging from the junction of the scallops to the bottom, the curved lines from one scallop intersecting those from other scallops and producing substantially diamond-shaped figures, 50 substantially parallel lines extending upward from the bottom and intersecting the curved diverging lines, and an upper and lower series of figures formed by the several lines, having substantially parallel sides and pointed ends, the lower series of said figures extending between two adjacent points of the star. 55

DANIEL FORBES.
